APPARATUS FOR ASSEMBLING FINS AND
THE LIKERobert C. Stutz, Buffalo, N. Y., assignor to
Niagara Blower Company, New York, N. Y., a
corporation of New York

Application September 12, 1944, Serial No. 553,745

18 Claims. (CL. 214—8)

1

This invention relates to apparatus for assembling fins or the like, particularly the metal fins used to provide an extended surface on heating or cooling coils, the fins being assembled in a predetermined parallel face-to-face spaced relationship and having registering openings through which the tubes are inserted, the tubes being subsequently expanded or otherwise united to each fin so that the fins serve to provide an extended surface for the tubes and increase the rate of heat transfer between the fluid flowing through the tubes and the air or other medium flowing past the fins and tubes.

One of the principal objects of the invention is to provide an extremely simple apparatus for successively dropping the fins from a stack, one at a time, into a form in properly spaced relationship to provide a finned structure having the fins in the desired spaced relationship and position.

Another object is to provide such apparatus which will deposit the fins at a high rate of speed, the apparatus being capable of depositing fins at a spacing of seven fins per inch at a rate of 220 fins per minute.

Another object is to provide such apparatus which will deposit the fins accurately and positively so that the machine does not jam in its operation and so that the operator is not required to go along behind the apparatus and straighten misplaced fins.

Another aim is to provide such apparatus which is self-contained and easily portable so that after a group of fins has been deposited in one form, the apparatus can be lifted to another form to continue its operation while tubes are being inserted in the assembled fins.

Another purpose is to provide such apparatus which is free from the necessity of close supervision and which will deposit fins from a stack of a substantial quantity so that the operator is free to set up the apparatus for inserting and expanding the tubes while the apparatus is depositing the fins.

Another aim is to provide such apparatus which is readily adjustable to deposit the fins at any desired spacing.

Other objects are to provide such apparatus which is simple and inexpensive in construction and which will stand up under conditions of severe and constant use without getting out of order or requiring repairs.

In the accompanying drawings:

Fig. 1 is a side elevation of a fin assembling machine embodying the present invention and

2 showing the same mounted on a form which is internally grooved to receive the fins in the desired spaced relation.

Fig. 2 is a vertical central sectional view through the apparatus and showing a part of the form in elevation.

Fig. 3 is a fragmentary view similar to Fig. 2 and showing one of the fins released and about to drop into the form.

Fig. 4 is a transverse sectional view through the form showing the rear end of the apparatus.

Figs. 5 and 6 are fragmentary vertical sectional views, taken on the correspondingly numbered lines on Fig. 3.

Fig. 7 is a fragmentary vertical sectional view, taken on line 1—7, Fig. 4.

Fig. 8 is a wiring diagram of the motor and start and stop switch of the apparatus.

The apparatus forming the subject of the present invention is particularly designed to assemble the metal fins 10 used in fabricating extended fin surfaced heating and cooling coils, these fins being of rectangular outline and having regularly spaced tube receiving circular openings 11 therein, the metal from each of these openings being formed to provide an annular nipple 12, these nipples projecting outwardly from one face of each fin. The machine embodying the present invention assembles these fins 10 in face-to-face equally spaced relationship with the corresponding openings and nipples 11, 12 of the fins in register with each other so that tubes (not shown) can be threaded through the registering openings 11 to be subsequently expanded or otherwise rigidly secured to the nipples 12 thereof.

For this purpose the apparatus forming the subject of the present invention drops the fins one at a time, from a stack of fins, edgewise into a form which is internally grooved to receive the fins in the desired spacing, this form preferably being constructed as follows:

The numeral 16 represents an elongated base suitably supported on legs 18. This base carries a pair of elongated side walls 18 which extend lengthwise along the sides of the base and form between them an elongated fin receiving channel indicated generally at 16. An angle iron 20 is secured to the outer face of each of the side walls 18 along the top edge thereof, the two angle irons 20 forming the two rails of a track for supporting the apparatus forming the subject of the invention as hereinafter described. The opposing faces of the side walls 18 of the form are vertically grooved, as indicated at 21, to provide registering fin receiving slots of the desired spacing and

each pair of which are adapted to receive the opposite longitudinal edges of one of the fins 10. At the upper end of each slot 21 the metal between the slots is chamfered or beveled, as indicated at 22, this bevel extending upwardly and to the right, as viewed in Figs. 2 and 3, and serving to provide an enlarged mouth at the upper end of each of the fin receiving grooves 21 as well as to provide a small angular face for guiding the lower edge of each of the fins 10 into each groove.

The fin assembling apparatus is in the form of a self-propelled carriage, indicated generally at 25, which rides along the rails 20 of the form and containing a stack of fins 10, a mechanism being provided on the carriage for dropping the fins one at a time into the successive pairs of opposing grooves 21 of the form. The carriage is shown as comprising a pair of vertical side plates 26 which are rigidly connected together as herein-after described and each side plate being supported by a pair of rollers 28 which ride on the corresponding rail 20. The carriage can be additionally guided along the rails 20 by a pair of side rollers 29 depending from each side plate 26 and engaging the opposing sides of the side plates 18.

An electric motor 30 is secured to the outer face of one of the side plates 26 and, through a reducing gear 31, drives a cross shaft 32 which is suitably journaled in the side plates 26. Within the carriage a pinion 33 is fast to this cross shaft 32, this pinion meshing with a gear 34 fast to a main drive shaft 35, the ends of this main drive shaft being likewise suitably journaled in the side plates 26 of the carriage. A pair of gear wheels 36 are secured to this main drive shaft 35 adjacent the side plates 26 and, as best shown in Fig. 6, have teeth which mesh with the chamfered or beveled upper ends 22 of the fin receiving slots 21 in the side walls 18 of the form. It will therefore be seen that the motor 30 in driving these gear wheels 36 serves to propel the carriage 25 along the rails 20 on its rollers 28, the movement of the carriage being from left to right as viewed in Figs. 1-3.

The rear ends of the two side plates 26 of the carriage are connected by a rod 40 on which a platform 41 is pivotally mounted, this platform extending across the space between the two side plates 26 and having a free end at the rear end of the carriage which is capable of being moved up and down by virtue of the pivotal mounting of the platform on the cross rod 40. This platform is adapted to support a stack of the fins 10, these fins being arranged with their longitudinal edges along the opposing faces of the side walls 26 and in a generally vertical position, the stack of fins leaning rearwardly or toward the left, as viewed in Figs. 1-3, and being supported by the ends of a pair of set screws 42 mounted in a block 43 carried by a cross-piece 44 which connects the rear ends of the two side plates 26 and is shown as secured to outwardly extending vertical flanges 45 thereof by screws 46. The rear end of each of the set screws 42 is slotted and accessible from the rear of the machine, as best shown in Fig. 4, and a lock nut 48 is provided on each of these set screws, thereby to determine the angular position of the stack 70 of fins 10 bearing against the forward ends of the set screws.

The rearmost fin of the stack of fins 10 on the platform 41 is split from the stack and dropped into a corresponding pair of opposed slots 21 in

the form in timed relation to the movement of the carriage 25 along the rails 20. For this purpose the free end of the platform 41 carrying the stack of fins 10 is moved up and down in timed relation to the travel of the carriage. This is accomplished by a star wheel 50 which is fast to the main shaft 35 and having its teeth engaging with the pointed end of a screw 51 secured in a bracket 52 supporting the free end of the platform 41. This pointed screw 51 can be held in proper relation to the teeth of the star wheel 50 by a lock nut 53. It will be seen that as the main drive shaft 35 rotates, the corresponding tooth of the star wheel 50 lifts the pointed screw 51. When the point of this screw travels beyond the edge of this tooth of the star wheel it drops down onto the next succeeding tooth of the star wheel. Since the pointed pin 51 is fast to the free end of the platform, it will be seen that this free end of the platform will be moved up and down, for each revolution of the main shaft 35, a number of times equal to the number of teeth on the star wheel 50.

An angular guide rail 55 is secured to the inner face of each side plate 26, the lower end of this guide rail being arranged adjacent the rearmost end of the lower edge of the corresponding side plate 26 while its upper pointed end 56 is arranged adjacent the rearmost extremity or free end of the platform 41 and is formed to provide a forwardly facing face which forms an abutment to retain the stack of fins 10 on the platform. These guide rails 55 coact with a curved pointed finger 58 to split the rearmost fin 10, at its lower end, from the stack each time the platform 41 is moved to its elevated position. For this purpose the finger 58 is mounted on the rear end of a bell crank lever 59 which is pivoted at the center of the free end of the platform 41 to swing about an axis parallel with the axis of oscillation of the platform 41. The upwardly extending pointed end of the curved finger 58 works through a notch 60 provided at the free edge of the platform 41 and when the bell crank lever 59 is rotated clockwise, as viewed in Figs. 2 and 3, the curved finger 58 enters between the last two fins 10 of the stack of fins on the platform 41.

That end of the bell crank lever 59 extending toward the front end of the carriage is connected by a vertical link 62 with a cross rod 63 between the two side plates 26 of the carriage. Since this rod is rigid with the carriage, it will be seen that as the free end of the platform 41 is moved upwardly, toward the position shown in Fig. 3, the curved finger likewise is moved upwardly through the notch 60 and between the last two fins 10 on this platform. When the platform 41 passes above the pointed ends 56 of the two side rails 55, the curving form of the finger 58 pushes the lower end of the rearmost fin 10 rearwardly and guides it onto the guide rails 55 down which it is free to fall. At the same time the finger 58 acts as a detent to prevent the next succeeding fin 10 of the stack from being released until the next succeeding elevation of the platform 41 by the star wheel 50.

To insure the proper coaction between the curved finger 58 in releasing the endmost fin 10, it is desirable that it be adjustably mounted on the end of the bell crank lever 59. To this end, as best shown in Fig. 7, this curved finger 58 is preferably secured to the end of the bell crank lever 59 by a screw 65 extending through a longitudinal slot 66 in the finger 58. Upon loosening the screw 65 the curved finger can be adjusted

up or down along its slot 66 thereby to precisely adjust the timing of the pushing action of this finger on the endmost fin 10.

To insure the free fall of the endmost fin of the stack of fins on the platform 41, means are also provided for positively splitting off this fin at its top, as well as at its bottom, as just described. To this end a strip 68 of spring metal is secured to the center of the block 43 carried by the crosspiece 49, this strip projecting from the block 43 toward the front end of the machine. At its free end this spring strip 68 carries a V-shaped tooth 69 having an inclined face 70 toward the front of the carriage and having an abrupt or vertical face 71 toward the rear of the carriage. The upper ends of the leaning stack of fins 10 are supported by the inclined face 70 of this tooth. When, however, the platform swings down to its fully depressed position the upper ends of the stack of fins falls toward the rear of the carriage under the tooth 69 until the rearmost fin engages the ends of the two set screws 42 carried by the block 43. These set screws are so adjusted that on the next upward movement of the platform 41 the tooth 69 enters between the last two fins 10 of the stack and thereby splits off the rearmost fin. At the time when the platform 41 reaches the upper extremity of its movement and the lower edge of the rearmost fin is released, the uppermost edge of this fin is likewise released.

In order to guide the lower edge of the falling fin 10 into its proper pair of the slots 21, a leaf spring 72 is secured to and forms an extension of the upper face of each of the guide rails 55. These springs engage the chamfered or bevel faces 22 at the upper ends of these slots and insure that the lower edge of the falling fin is guided into the proper pair of slots 21. Since the leaf springs 72 are flexible, they readily click along the chamfered faces 22 as the carriage moves along the form.

It is important, of course, that the fins be in a vertical position when they fall vertically into the slots 21. It has been found by experience that the lower edges of the falling fins, if unrestrained, tend to swing beyond a vertical position before they enter the predetermined pair of slots. To restrain this tendency, spring leaves 73 are secured to the outside of the side plates 23 of the carriage by bolts 74 each extending through a longitudinal slot 77 in the spring leaf so that these leaves are adjustable forwardly and rearwardly. The free rear end of these spring leaves 73 are each formed to provide an inwardly projecting finger 78 which projects through a hole 79 in the corresponding side plate 23 of the carriage. These fingers 78 are in the path of the opposite vertical edges of the fins 10 and engage the lower parts of these fins just before the lower edges of the fins enter the pair of grooves 21 of the forms. These spring fingers 78 are inclined inwardly and toward the trailing end of the carriage so as to be brushed aside by the passing fins but exert a restraining effect which serves to insure that each fin is in a vertical position as it falls into its pair of slots 21.

To determine the number of fins which the apparatus will deposit in its travel, a pin 80 can be arranged, either fixed or adjustably, along one of the rails 20. On the carriage a start and stop switch 81 can be mounted so that its operating lever 82 engages this pin 80 when the carriage reaches this point in its travel along the rails 20. The movement of the switch lever 82 against this pin 80 serves to open the switch and by arranging

this switch in series with the motor 30, as shown in Fig. 8, the carriage will be automatically stopped after a predetermined number of fins 10 have been deposited as determined by the setting or position of the pin 80.

In operation the drive connection between the motor 30 and the main drive shaft 35 rotates the pair of gear wheels 36 on this shaft and since the teeth of these gear wheels mesh with the chamfered ends 22 at the upper ends of the slots 21 in the side walls 18 of the form, the carriage 25 is propelled along the form, riding with its rollers 28 on the rails 20 forming the top of the side walls 18 of the form. The movement of the carriage 25 is from left to right, as viewed in Figs. 1-3. Sidewise movement of the carriage 25 off of the rails 20 is prevented by the pairs of side rollers 29 which engage the sides of the walls 18. This self-propelled movement of the carriage is continued until the lever 82 of the stop switch 81 on the carriage engages the pin 80 on the form, this switch being opened on engaging the pin and de-energizing the motor 30 which is in series with it.

The rotation of the main drive shaft 35 also rotates the star wheel 50 fast thereto, this causing each tooth of this star wheel to lift the pointed pin 51 and then permit this pin to fall back to the next succeeding tooth of this star wheel. Since the pointed pin 51 is fixed to the free rear end of the platform 41 by the bracket 52, this vertically reciprocating movement of the pointed pin 51 is transmitted to the platform 41.

The fins 10 are stacked upon this platform 41 in the position shown in Fig. 3. Each time the platform 41 reciprocates downwardly the upper end of the rearmost fin 10 is freed from the inclined rear face 70 of the tooth 69 carried by the metal strip 68 and falls against the forward ends of the pair of set screws 42. On the next upward movement of the platform 41, the finger 58 is brought between the last two fins of the pack thereby splitting off the upper end of the endmost fin to permit it to fall but retaining the balance of the stack of fins upon the platform 41.

In the lowered position of the platform 41 the stack of fins on this platform is retained thereon by the engagement of the upper pointed ends 56 of the two guide rails 55 with the face of the endmost fin. As the platform rises the curved finger 58 is swung upwardly so as to be interposed between the last two fins and also to shove and guide the lower end of the endmost fin over the pointed ends 56 of the guide rails 55. This upward movement of the curved finger is effected by its mounting on one end of the bell crank lever 59, the other end of this bell crank lever being connected by the link 62 to the cross rod 63 of the carriage frame. Upward movement of the platform 41 thereby rotates the bell crank lever 59 clockwise as viewed in Figs. 2 and 3.

Since on the extreme upward movement of the platform 41 the upper end of the endmost fin 10 is released with the balance of the stack held at the top by the tooth 69, and since at this time the lower end of the endmost fin 10 has been pushed over the pointed upper end of the two guide rails 55 by the curved finger 58 with the balance of the stack held at the bottom by the curved finger 58, it will be seen that the endmost fin is free to fall, as indicated by full lines in Fig. 3 and by dotted lines in Fig. 2.

The lower end of the falling endmost fin is guided into the proper pair of slots 21 by the guide rails 55 and the spring leaves 72 projecting from the ends of these guide rails. The

tendency of the lower end of the falling fin to swing rearwardly beyond a vertical position on sliding down the guide rails 55 is restrained by the spring fingers 18 which project inwardly from the opposite side plates 26 of the carriage and are brushed aside by the falling fin but serve to restrain its lower end sufficiently so that the fin is vertical on entering the slots 21 and falls freely into the same.

If it is desired to use the apparatus with a form having a different spacing of slots 21 so as to provide a finned structure having more or less fins to the inch, all that is necessary to adapt the apparatus to this new condition is to change the star wheel 50 and the two wheels 38 to ones having an appropriate number of teeth. Since the timing of the movement of the carriage to the dropping of the fins is determined by this star wheel 50 and the two wheels 38, it will be seen that any desired timing can be secured by so changing these wheels.

From the foregoing it will be seen that the present invention provides an extremely portable and inexpensive apparatus for assembling fins in a form. Further, the apparatus is extremely rapid in its operation, deposits the fins with a high degree of accuracy and operates with little supervision or service difficulties.

I claim as my invention:

1. In a machine for fabricating finned structures and the like, a frame forming a fin receiving form, fin retaining means mounted on said frame and providing vertical spaced grooves for receiving edge portions of the fins, a carriage mounted to travel along said retaining means, a platform on said carriage for holding a stack of fins each in an upright position generally in alignment with said grooves and with an endmost fin arranged at one extremity of said platform, means on said carriage adjacent said extremity of said platform for successively splitting off said endmost fins from said stack and shifting them in a direction transverse of their faces to a position beyond said extremity of said platform comprising retaining finger means mounted on said carriage for movement into the space between the endmost fin and the next following fin, and means actuated in timed relation to the movement of said carriage and moving said finger means relative to said stack to enter said space and push the endmost fin to a position beyond the extremity of said platform, and means on said carriage providing a way permitting said split off fins to fall by gravity in a substantially vertical position into said vertical spaced grooves.

2. In a machine for fabricating finned structures and the like, a frame forming a fin receiving form, fin retaining means mounted on said frame and providing vertical spaced grooves for receiving edge portions of the fins, a carriage mounted to travel along said retaining means, a platform on said carriage for holding a stack of fins in upright position generally in alignment with said grooves and with an endmost fin arranged at one extremity of said platform, and means on said carriage adjacent said extremity of said platform for successively splitting off said endmost fins from said stack and shifting them in a direction transverse to their faces to a position beyond said extremity of said platform, comprising wedge-shaped finger means mounted on said carriage for endwise movement into the space between the endmost fin and the next following fin and means actuated in timed relation to the movement of said carriage and

5 moving said wedge-shaped finger means endwise relative to said stack to enter said space and push off the endmost fin to a position beyond the extremity of said platform, said successively split off fins falling edgewise by gravity into said vertical spaced grooves.

3. In a machine for fabricating finned structures and the like, a frame forming a fin receiving form, fin retaining means mounted on said frame and providing vertical spaced grooves for receiving edge portions of the fins, a carriage mounted to travel along said retaining means, a platform on said carriage for holding a stack of fins in upright position generally in alignment with said grooves and with an endmost fin arranged at one extremity of said platform, means on said carriage adjacent said extremity of said platform for successively splitting off said endmost fins from said stack and shifting them in a direction transverse to their faces to a position beyond said extremity of said platform, comprising a stop mounted on said carriage and engaging the exposed face of the endmost fin and a finger mounted on said carriage for movement into the space between the endmost fin retained by said stop and means for moving said stack relative to said stop and finger in a direction generally parallel with the plane of said endmost fin to alternately move said stop and finger to and from operative positions, said successively split off fins falling edgewise by gravity into said vertical spaced grooves, and means synchronizing the movement of said splitting off means with the movement of said carriage to fill said grooves in regular order.

4. In a machine for fabricating finned structures and the like, a frame forming a fin receiving form, fin retaining means mounted on said frame and providing vertical spaced grooves for receiving edge portions of the fins, a carriage mounted to travel along said retaining means, a platform on said carriage for holding a stack of fins in upright position generally in alignment with said grooves and with an endmost fin arranged at one extremity of said platform, means on said carriage adjacent said extremity of said platform for successively splitting off said endmost fins from said stack and shifting them in a direction transverse to their faces to a position beyond said extremity of said platform, comprising a pair of fingers mounted on said carriage on opposite sides of said stack for movement into the space between the endmost fin and the next following fin, and means actuated in timed relation to the movement of said carriage and moving said pair of fingers relative to said stack to alternately enter said space and transfer the endmost fin to a position beyond the extremity of said platform, said successively split off fins falling edgewise by gravity into said vertical spaced grooves, and means on said carriage beyond said extremity of said platform for guiding said fins so falling into said vertical spaced grooves.

5. In a machine for fabricating finned structures and the like, a frame forming a fin receiving form, fin retaining means mounted on said frame and providing vertical spaced grooves for receiving edge portions of the fins, a carriage mounted to travel along said retaining means, a platform on said carriage for holding a stack of fins in upright position generally in alignment with said grooves and with an endmost fin arranged at one extremity of said platform, means on said carriage adjacent said extremity of said

platform for successively splitting off said endmost fins from said stack and shifting them in a direction transverse to their faces to a position beyond said extremity of said platform, comprising a pair of stops mounted on said carriage and engaging opposite sides of the exposed face of the endmost fin, and a pair of fingers mounted on the carriage each adjacent each stop for movement into the space between the endmost fin retained by said stop and means actuated in timed relation to the movement of said carriage and moving said pairs of fingers and stops in a direction generally parallel with the plane of said endmost fin to alternately move each stop and its companion finger to and from operative positions, said successively split off fins falling edgewise by gravity into said vertical spaced grooves, and a guide rail on said carriage extending downwardly from adjacent said extremity of said platform and guiding the lower edges of said fins so falling into said vertical spaced grooves.

6. In a machine for fabricating finned structures and the like, a frame forming a fin receiving form, fin retaining means mounted on said frame and providing vertical spaced grooves for receiving edge portions of the fins, a carriage mounted to travel along said retaining means, a platform pivotally mounted on said carriage adjacent one of its ends to move about a horizontal axis extending transversely of the line of movement of said carriage, means successively moving the opposite free end of said platform up and down, said platform holding a stack of fins in upright position in alignment with said grooves and with an endmost fin arranged at the extremity of said free end of said platform, and means actuated through motion derived from the up and down movement of said free end of said platform for splitting off the endmost fin from said stack each time the free end of the platform moves in one direction and shifting said split off fin in a direction transverse of its face to a position beyond said extremity of said platform, said split off fins falling edgewise by gravity into said vertical spaced grooves.

7. In a machine for fabricating finned structures and the like, a frame forming a fin receiving form, fin retaining means mounted on said frame and providing vertical spaced grooves for receiving edge portions of the fins, a carriage mounted to travel along said retaining means, a platform pivotally mounted on said carriage adjacent one of its ends to move about a horizontal axis extending transversely of the line of movement of said carriage, means successively moving the opposite free end of said platform up and down, said platform holding a stack of fins in upright position in alignment with said grooves and with an endmost fin arranged at the extremity of said free end of said platform, and means actuated through motion derived from the up and down movement of said free end of said platform for splitting off the endmost fin from said stack each time the free end of the platform moves in an upward direction and shifting said split off fin in a direction transverse of its face to a position beyond said extremity of said platform, said split off fins falling edgewise by gravity into said vertical spaced grooves.

8. In a machine for fabricating finned structures and the like, a frame forming a fin receiving form, fin retaining means mounted on said frame and providing vertical spaced grooves

for receiving edge portions of the fins, a carriage mounted to travel along said retaining means, a platform pivotally mounted on said carriage adjacent one of its ends to move about a horizontal axis extending transversely of the line of movement of said carriage, means synchronized with the movement of said carriage along said frame and successively moving the opposite free end of said platform up and down, said platform holding a stack of fins in upright position in alignment with said grooves and with an endmost fin arranged at the extremity of said free end of said platform, and means actuated through motion derived from the up and down movement of said free end of said platform for splitting off the endmost fin from said stack each time the free end of the platform moves in one direction and shifting said split off fin in a direction transverse of its face to a position beyond said extremity of said platform, said split off fins falling edgewise by gravity into said vertical spaced grooves.

9. In a machine for fabricating finned structures and the like, a frame forming a fin receiving form, fine retaining means mounted on said frame and providing vertical spaced grooves for receiving edge portions of the fins, a carriage mounted to travel along said retaining means, a platform pivotally mounted on said carriage adjacent one of its ends to move about a horizontal axis extending transversely of the line of movement of said carriage, means successively moving the opposite free end of said platform up and down, said platform holding a stack of fins in upright position generally in alignment with said grooves and with an endmost fin arranged at the extremity of said free end of said platform, means mounted on said free end of said platform and actuated through motion derived from the up and down movement of said free end of said platform for splitting off the lower end of the endmost fin from said stack each time the free end of the platform moves in an upward direction and shifting said lower end of said split off fin in a direction transverse of its face to a position beyond said extremity of said platform, and means mounted on said carriage above the free end of said platform and actuated through motion derived from the up and down movement of said free end of said platform for splitting off the upper end of the endmost fin from said stack each time the free end of the platform moves in an upward direction, said split off fins falling edgewise by gravity into said vertical spaced grooves.

10. In a machine for fabricating finned structures and the like, a frame forming a fin receiving form, fin retaining means mounted on said frame and providing vertical spaced grooves for receiving edge portions of the fins, a carriage mounted to travel along said retaining means, a platform pivotally mounted on said carriage adjacent one of its ends to move about a horizontal axis extending transversely of the line of movement of said carriage, means successively moving the opposite free end of said platform up and down, said platform holding a stack of fins in upright position generally in alignment with said grooves and with an endmost fin arranged at the extremity of said free end of said platform, means mounted on said free end of said platform and actuated through motion derived from the up and down movement of said free end of said platform for splitting off the lower end of the endmost fin from said stack each time the free end of

the platform moves in an upward direction and shifting said lower end of said split off fin in a direction transverse of its face to a position beyond said extremity of said platform, and means mounted on said carriage above the free end of said platform and actuated through motion derived from the up and down movement of said free end of said platform for splitting off the upper end of the endmost fin from said stack each time the free end of the platform moves in an upward direction and comprising a tooth mounted on said carriage adjacent the top of said stack and in position to be interposed between said endmost fin and the next succeeding fin when said free end of said platform is elevated, said split off fins falling edgewise by gravity into said vertical spaced grooves.

11. In a machine for fabricating finned structures and the like, a frame forming a fin receiving form, fin retaining means mounted on said frame and providing vertical spaced grooves for receiving edge portions of the fins, a carriage mounted to travel along said retaining means, a platform pivotally mounted on said carriage adjacent one of its ends to move about a horizontal axis extending transversely of the line of movement of said carriage, means successively moving the opposite free end of said platform up and down, said platform holding a stack of fins in upright position generally in alignment with said grooves and with an endmost fin arranged at the extremity of said free end of said platform, means mounted on said free end of said platform and actuated through motion derived from the up and down movement of said free end of said platform for splitting off the lower end of the endmost fin from said stack each time the free end of the platform moves in an upward direction and shifting said lower end of said split off fin in a direction transverse of its face to a position beyond said extremity of said platform, and means mounted on said carriage above the free end of said platform and actuated through motion derived from the up and down movement of said free end of said platform for splitting off the upper end of the endmost fin from said stack each time the free end of the platform moves in an upward direction and comprising a tooth mounted on said carriage adjacent the top of said stack and in position to be interposed between said endmost fin and the next succeeding fin when said free end of said platform is elevated and an abutment mounted on said carriage for adjustment lengthwise of its line of movement and in position to receive between it and said tooth said endmost fin when said free end of said platform is elevated, said split off fins falling edgewise by gravity into said vertical spaced grooves.

12. In a machine for fabricating finned structures and the like, a frame forming a fin receiving form, fin retaining means mounted on said frame and providing vertical spaced grooves for receiving edge portions of the fins, a carriage mounted to travel along said retaining means, a platform pivotally mounted on said carriage adjacent one of its ends to move about a horizontal axis extending transversely of the line of movement of said carriage, means successively moving the opposite free end of said platform up and down, said platform holding a stack of fins in upright position generally in alignment with said grooves and with an endmost fin arranged at the extremity of said free end of said platform, means mounted on said carriage above the free end of said platform and actuated through motion de-

rived from the up and down movement of said free end of said platform for splitting off the upper end of the endmost fin from said stack each time the free end of the platform moves in an upward direction, and means mounted on the free end of said platform and actuated through motion derived from the up and down movement of said free end of said platform for splitting off the lower end of the endmost fin from said stack each time the free end of the platform moves in an upward direction and shifting said lower end of said split off fin in a direction transverse of its face to a position beyond the extremity of said platform, comprising an upwardly projecting finger mounted on said free end of said platform in position to be moved upwardly to be interposed between said endmost fin and the next succeeding fin and means for moving said finger upwardly into engagement with said endmost fin and the next succeeding fin when said platform is raised, said split off fins falling edgewise by gravity into said vertical spaced grooves.

13. In a machine for fabricating finned structures and the like, a frame forming a fin receiving form, fin retaining means mounted on said frame and providing vertical spaced grooves for receiving edge portions of the fins, a carriage mounted to travel along said retaining means, a platform pivotally mounted on said carriage adjacent one of its ends to move about a horizontal axis extending transversely of the line of movement of said carriage, means successively moving the opposite free end of said platform up and down, said platform holding a stack of fins in upright position generally in alignment with said grooves and with an endmost fin arranged at the extremity of said free end of said platform, means mounted on said carriage above the free end of said platform and actuated through motion derived from the up and down movement of said free end of said platform for splitting off the upper end of the endmost fin from said stack each time the free end of the platform moves in an upward direction, and means mounted on the free end of said platform and actuated through motion derived from the up and down movement of said free end of said platform for splitting off the lower end of the endmost fin from said stack each time the free end of the platform moves in an upward direction and shifting said lower end of said split off fin in a direction transverse of its face to a position beyond the extremity of said platform, comprising an upwardly projecting finger mounted on said free end of said platform in position to be moved upwardly to be interposed between said endmost fin and the next succeeding fin and means for moving said finger upwardly into engagement with said endmost fin and the next succeeding fin when said platform is raised, comprising a bell crank lever pivotally secured to said platform, means securing said finger to one arm of said bell crank lever and a link connecting the other arm of said bell crank lever with said carriage, said split off fins falling edgewise by gravity into said vertical spaced grooves.

14. In a machine for fabricating finned structures and the like, a frame forming a fin receiving form, fin retaining means mounted on said frame and providing vertical spaced grooves for receiving edge portions of the fins, a carriage mounted to travel along said retaining means, a platform pivotally mounted on said carriage adjacent one of its ends to move about a horizontal axis extending transversely of the line of movement of said carriage, means successively moving the op-

posite free end of said platform up and down, said platform holding a stack of fins in upright position generally in alinement with said grooves and with an endmost fin arranged at the extremity of said free end of said platform, means mounted on said carriage above the free end of said platform and actuated through motion derived from the up and down movement of said free end of said platform for splitting off the upper end of the endmost fin from said stack each time the free end of the platform moves in an upward direction, an inclined guide rail mounted on said carriage and having its upper end arranged to engage the face of the endmost fin of said stack when said free end of said platform is in a lowered position and thereby retain said stack on said platform and means mounted on the free end of said platform and actuated through motion derived from the up and down movement of said free end of said platform for splitting off the lower end of the 20 endmost fin from said stack each time the free end of the platform moves in an upward direction and shifting said lower end of said split off fin in a direction transverse of its face and over said upper end of said inclined guide rail, 25 said split off fins falling edgewise by gravity down said guide rail into said vertical spaced grooves.

15. In a machine for fabricating finned structures and the like, a frame forming a fin receiving form, fin retaining means mounted on said frame and providing vertical spaced grooves for receiving edge portions of the fins, a carriage mounted to travel along said retaining means, a platform on said carriage for holding a stack of fins in upright position generally in alinement with said grooves and with an endmost fin arranged at one extremity of said platform, means on said carriage adjacent said extremity of said platform for successively splitting off said endmost fins from said stack and shifting them in a direction transverse to their faces to a position beyond said extremity of said platform, said successively split off fins falling edgewise by gravity into said vertical spaced grooves, a guide rail on said carriage extending downwardly from adjacent said extremity of said platform and guiding the lower edges of said fins so falling, and a leaf spring at the lower end of said guide rail and engaging said form at the upper ends of said vertical spaced grooves and guiding the lower 40 edges of the falling fins into said grooves.

16. In a machine for fabricating finned structures and the like, a frame forming a fin receiving form, fin retaining means mounted on said frame and providing vertical spaced grooves for 45

5 receiving edge portions of the fins, a carriage mounted to travel along said retaining means, a motor mounted on said carriage, a gear wheel mounted on said carriage and having teeth engaging said grooves, means operatively connecting said gear wheel and motor whereby said carriage is propelled along said retaining means by engagement of the teeth of said gear wheel with said grooves, supporting means on said carriage holding a stack of fins, and means on said carriage and synchronized with said gear wheel for removing fins from said stack and depositing them in the spaced grooves in said retaining means.

10 17. In a machine for fabricating finned structures and the like, a frame forming a fin receiving form, fin retaining means mounted on said frame and providing vertical spaced grooves for receiving edge portions of the fins, a carriage mounted to travel along said retaining means, a motor mounted on said carriage, a gear wheel mounted on said carriage and having teeth engaging said grooves, means operatively connecting said gear wheel and motor whereby said carriage is propelled along said retaining means by engagement of the teeth of said gear wheel with said grooves, supporting means on said carriage holding a stack of fins, a star wheel rotated by said motor in synchronism with said gear wheel and means actuated by the teeth of said star wheel for removing fins from said stack and depositing them in said spaced grooves in said retaining means.

15 18. In a machine for fabricating finned structures and the like, a frame forming a fin receiving form, fin retaining means mounted on said frame and providing vertical spaced grooves for receiving edge portions of the fins, a carriage mounted to travel along said retaining means, a motor mounted on said carriage, a gear wheel mounted on said carriage and having teeth engaging said grooves, means operatively connecting said gear wheel and motor whereby said carriage is propelled along said retaining means by engagement of the teeth of said gear wheel with said grooves, supporting means on said carriage holding a stack of fins in an upright position, means on said carriage for successively splitting off the endmost fins from said stack, and means synchronized with said gear wheel for operating said splitting off means, the fins so successively split off from said stack falling edgewise by gravity into said vertical spaced grooves.

ROBERT C. STUTZ.
